(57) **CLAIM**

The ornamental design for a bra, as shown and described.

DESCRIPTION

FIG. 1 is a front and right perspective view of a bra;

FIG. 2 is a front view thereof;

FIG. 3 is a rear view thereof;

FIG. 4 is a right view thereof; and,

FIG. 5 is a left view thereof.

The broken lines in the drawings are included for the purpose of illustrating portions of the bra that form no part of the claimed design. The dash dot lines in FIG. 1 depict a figure which forms no part of the claim. FIGS. 3-5 show the bra with symbolic breaks in the straps. The appearance of any portion of the article between the break lines forms no part of the claim.
